UNITED STATES PATENT OFFICE.

GEORGE L. SPLITT, OF SUMMERDALE, ALABAMA.

VENDING-MACHINE.

1,196,404.

Specification of Letters Patent. Patented Aug. 29, 1916.

Application filed September 22, 1915. Serial No. 52,015.

To all whom it may concern:

Be it known that I, GEORGE L. SPLITT, a citizen of the United States, residing at Summerdale, in the county of Baldwin and 5 State of Alabama, have invented certain new and useful Improvements in Vending-Machines, of which the following is a specification.

My invention relates to improvements in 10 vending machines, adapted to deliver bottles containing beverages or the like, while not necessarily restricted to this use.

An important object of the invention is to provide a machine of the above mentioned 15 character, so constructed that the elements which serve or vend the bottle or other article, is manually operated, upon being released, in a convenient manner, whereby no complicated mechanism is employed to move 20 the same.

A further object of the invention is to provide a machine of the above mentioned character; adapted to be constructed in a number of units, which may be inclosed 25 within a refrigerator casing so that the bottled beverage may be kept cool, in an economical manner.

A further object of the invention is to provide a machine of the above mentioned 30 character, formed of few and simple parts, which are arranged in a compact manner.

A further object of the invention is to provide a machine of the above mentioned character, having means for indicating the 35 number of bottles remaining in each unit, or the number of bottles which have been removed therefrom.

Other objects and advantages of the invention will be apparent during the course 40 of the following description.

In the accompanying drawings forming a part of this specification and in which like numerals are employed to designate like parts throughout the same, Figure 1 is a 45 front elevation of a machine embodying the invention, Fig. 2 is a fragmentary horizontal section taken on line 2—2 of Fig. 1, Fig. 3 is a vertical longitudinal sectional view taken on line 3—3 of Fig. 1, Fig. 4 is a 50 transverse sectional view taken on line 4—4 of Fig. 3, Fig. 5 is an enlarged detail section taken on line 5—5 of Fig. 1, Fig. 6 is an inner face view of a door showing the recording mechanism, and, Fig. 7 is a side elevation of a recording wheel.

In the drawings, wherein for the purpose

of illustration, is shown a preferred embodiment of my invention, the numeral 10 designates a casing, such as the casing of a refrigerator. Arranged within this casing are 60 pairs of horizontal longitudinal bars 11, rigidly attached thereto by any suitable means.

The machine is preferably constructed in vertical units, there being two compartments 65 12^a and 12^b in each unit, as will be apparent. Each unit comprises a pair of upper stationary guide rods 12, rigidly attached to the front 13 of the casing 10 and having their opposite ends spaced from the rear end of 70 the upper compartment, as shown. Mounted to slide upon the upper guide rods 12 are pairs of upper tubes 14, as shown. The rods 12 and tubes 14 constitute supporting means for the upper stratum of bottles in 75 the upper compartment 12^a, and when these tubes are moved forwardly an opening is provided in the bottom of the upper compartment, at its rear end, whereby a bottle may gravitate from the upper into the lower 80 compartment, as shown.

The numeral 15 designates lower stationary guide rods, rigidly attached to the rear end 16 of the casing 11. These guide rods receive lower tubes 17, adapted to slide 85 thereon. The forward ends of the tubes 17 extend exteriorly of the lower compartment and are rigidly attached to a reciprocating door 18, by any suitable means, such door being adapted to cover an opening 19 in the 90 forward end 13, which leads into the lower compartment 12^b, as shown. This door has a handle 19'. In order that the upper and lower pairs of rods 14 and 17 may move or reciprocate together, they are rigidly connected by means of curved straps 20. These straps are attached to the lower tubes 17, as shown at 21, and are connected with lugs 22, carried by the upper tubes, as more clearly shown in Fig. 4. The bars 11 support transverse shafts 23, rotatably receiving thereon grooved wheels or pulleys 24, upon which the lower tubes 17 travel, whereby the bulk of the weight of the bottles or the like to be vended are supported by these wheels. 100

Arranged between the bars 11 are pivoted checks, or fingers 25, carried by shafts 26, and having their rear ends counter-weighted, as shown at 27. The forward ends of these fingers are preferably bent, to provide 110 a head 28 adapted to move upwardly and engage behind the bottom of the bottle to

hold the bottle against rearward movement, but not interfering with the forward movement. The bars 11 also have checks or fingers 29 pivoted thereto as shown at 30, each of which is provided with a head 31, to contact with the top of the bottle at its mouth. The finger 29 prevents the forward movement of the bottle but permits of its free rearward movement.

10. Each unit, as clearly shown in Fig. 5, is provided near and above the rods 12 with an opening 32, leading into the compartment 12^a and through which the bottles are inserted to load the unit. The opening 32 is normally covered by a door 33, which is preferably hinged at its bottom, as shown at 34, (Fig. 1) and held in the closed position by a latch or lock means 35 of any well known or preferred type. This latch preferably embodies a handle 36, which may be employed in swinging the door to the opened and closed positions.

In order that the operator may ascertain the number of bottles which have been removed from each unit, or the number of bottles therein, each door 18, as more clearly shown in Fig. 5, is provided with a recess 37, receiving a rotatable indicator 38, having numerals 39 thereon in a circular group, as more clearly shown in Fig. 7. These numerals are adapted to be successively brought to an opening 40 formed in a protecting plate 41, secured to the door 18. The indicator disk 38 is turned by a shaft 42, having a ratchet wheel 43 rigidly attached thereto. This ratchet wheel is arranged upon the inner side of the door 18 and is adapted to be engaged by a vertical reciprocating pawl 44, operating in a guide 45, which will permit of sufficient lateral movement of the pawl to allow it to properly clear the teeth of the ratchet wheel upon its downward movement without rotating the ratchet wheel, but when this pawl moves upwardly it catches beneath the tooth of the ratchet wheel and positively advances it. The pawl 44 is moved downwardly by a spring 46, suitably connected therewith and carried by a pin 47, one end of the spring 50 being in the form of a shoulder 48, to engage with the teeth of the ratchet wheel to positively prevent back turning. The pawl 44 is moved upwardly by a lever 49, pivotally connected with its lower end and having a loose pivotal connection with the adjacent tube 17, as shown at 50.

In the operation of each unit, the door 33 is moved to the open position and three bottles inserted within the upper compartment 12^a of the unit. The door 18 of the lower compartment 12^b in each unit may now be moved to the outermost position, whereby the tubes 14 and 17 will move forwardly, as illustrated in the second unit from the top, 65 and finally to the position indicated in the

third unit from the top. This forward movement of the tubes is limited, when the forward ends of the tubes 14 contact with the end 13, and this movement is sufficient to permit of the removal of only one bottle 70 from the lower compartment 12^b. The rear-most bottle in the upper compartment 12^a will gravitate or drop into the rear end of the lower compartment 12^b in the unit, and will be supported therein by the rods 15. 75 When the rods 17 are moved inwardly, their rear portions take up and support the bottle in the lower compartment. A bottle may now be inserted in the upper compartment whereby the two bottles therein will move 80 rearwardly. Upon the forward movement of the rods 17, the first bottle in the lower compartment 12^b of the unit will be carried forwardly to the intermediate position, and the catch or lever 25 will have its head 28 85 engaging its rear end, preventing backward movement of the bottle. By continuing this operation the upper and lower compartments may be completely filled with bottles. It is apparent that the bottles are fed from 90 the upper compartment to the lower compartment, and in operation all of the bottles from the upper compartment will be discharged into the lower compartment.

To obtain a bottle from a unit the door 18 is drawn forwardly, to expose the forward bottle, which may be removed. The rear-most bottle in the upper compartment drops into the rear end of the lower compartment, as above indicated, and upon the return 100 movement of the door 18, the tubes 17 carry the next bottle in the upper compartment, to the rearmost position, the forward movement of this bottle being prevented by the catch or catches 29. Each time that the 105 door 18 is opened and closed, the lever 49 is swung upwardly by slidably contacting with the bottom wall of the opening 32. This movement of the lever 49 moves the pawl 44 upwardly for effecting a step movement of 110 the ratchet wheel 43, causing the next numeral 39 to appear in the opening 40.

It is to be understood that suitable coin controlled mechanism may be employed for normally locking each door 18 against movement and to release it upon the deposit of a suitable coin whereby it may be moved to the outer position.

It is to be understood that the form of my invention herewith shown and described is 120 to be taken as a preferred example of the same, and that various changes in the shape, size, and arrangement of parts may be resorted to without departing from the spirit of the invention or the scope of the subjoined claims.

Having thus described the invention, I claim:

1. In a machine of the character described, a casing embodying upper and lower com- 130

- partments, a movable support for the articles in the upper compartment and adapted when shifted in one direction to feed an article from the upper compartment into the lower compartment, a movable support for articles in the lower compartment and adapted when shifted in one direction to bring an article in the lower compartment to a position more or less exteriorly thereof, and means to move the supports.
2. In a machine of the character described, a casing embodying upper and lower compartments, a movable support for the articles in the upper compartment and adapted when shifted in one direction to feed an article from the upper compartment into the lower compartment, a movable support for the articles in the lower compartment and adapted when shifted in one direction to feed an article from the lower compartment, means for connecting the supports so that they move together, and means to move one support.
3. In a machine of the character described, a casing embodying upper and lower compartments, a substantially horizontal reciprocatory support for the articles in the upper compartment and adapted when moved in one direction to feed an article from the upper compartment into the lower compartment, a substantially horizontal reciprocatory support for articles in the lower compartment and adapted when moved in one direction to carry an article exteriorly of its compartment, means rigidly connecting the supports, and manually operated means to move one support.
4. In a machine of the character described, a casing embodying upper and lower compartments, a support for the articles in the upper compartment to move longitudinally therewith and adapted when shifted in one direction to feed an article from the upper compartment into the lower compartment, means adapted to prevent the articles moving longitudinally in one direction in the upper compartment, a support for the articles in the lower compartment to move longitudinally therewith and adapted when moved in one direction to carry an article to the exterior of its compartment, means adapted to prevent the articles moving longitudinally in one direction in the lower compartment, and means to move the supports.
5. In a machine of the character described, a casing embodying upper and lower compartments, stationary guide rods arranged between the compartments and extending longitudinally thereof and having corresponding ends spaced a substantial distance from one end of the compartments, upper tubes mounted to slide upon the guide rods and to provide an opening between their ends and one end of the upper compartment so that articles may pass from the upper compartment into the lower compartment, stationary guide rods arranged in the bottom of the lower compartment, lower tubes mounted to slide upon the second named stationary guide rods and adapted to be moved to a position exteriorly of the compartment, elements connecting the upper and lower tubes so that they move together, and means to move one tube.
6. In a machine of the character described, a casing embodying upper and lower compartments, upper stationary guide rods arranged in the bottom of the upper compartment and extending longitudinally thereof and having corresponding ends spaced a substantial distance from one end of the upper compartment, upper tubes mounted to slide upon the guide rods, lower stationary guide rods arranged in the bottom of the lower compartment, lower tubes mounted to slide upon the lower guide rods, pulleys arranged beneath the lower tubes for supporting them, elements connecting the upper and lower tubes, and means to move the lower tubes.

In testimony whereof I affix my signature in presence of two witnesses.

GEORGE L. SPLITT.
